CHARLES KELLOGG, OF DETROIT, MICHIGAN.

Letters Patent No. 74,377, dated February 11, 1868.

IMPROVED MACHINE FOR FORMING EYES ON METAL RODS.

The Schedule referred to in these Letters Patent and making part of the same.

TO ALL WHOM IT MAY CONCERN:

Be it known that I, CHARLES KELLOGG, of Detroit, in the county of Wayne, and State of Michigan, have invented new and useful Improvements in Machine for Forming Eyes on Metal Rods; and I do hereby declare that the following is a full, clear, and exact description thereof, which will enable those skilled in the art to make and use the same, reference being had to the accompanying drawings, forming part of this specification, in which—

Figure 1 is a plan view of my improved machine, showing the rod placed therein previous to being bent.

Figure 2 is a similar view, showing the rod bent by the action of the lever and stud.

Figure 3 shows the successive stages of formation of the eye.

Figure 4 is a section of the machine through the line $x\ x$, fig. 2.

Figure 5 is a section through the line $y\ y$, fig. 1.

Similar letters of reference indicate corresponding parts.

This invention relates to the formation of eyes in any metallic rods or bars, but is designed more particularly for the iron rods entering into the construction of bridges or other engineering structures, where it is important to preserve the integrity of iron at the eye, by retaining the normal parallel character of the fibres of the iron when the eye is being formed.

It consists of a frame-plate having an adjustable recess for holding the rod or bar near the eye to be formed, the said plate being provided with a bending device of a compound character, together with other improvements perfecting the whole, as will hereinafter be more fully set forth.

In the drawings, A is the frame-plate, which is in practice of cast metal. Bolted thereto, in the position shown, are two guide-plates, B and C, the proximate faces of which form respectively the bottom and one side of the recess for holding the rod, while the operation of bending the eye is being performed. The remaining side of this recess is provided by a slotted and bevelled plate, D, the slots a serving to permit its lateral adjustment for different-sized rods or bars, and its bevelled end contributing to the proper formation of the eye, as will be shown.

The position and operation of these plates are further shown by the section at fig. 5; the lateral adjustment of the plates B and C being permitted by the slots a' a'' , through which the screw-bolts b pass to secure them to the frame-plate A. Pivoted to the under side of the frame-plate is a lever, L, a part of which is shown dotted in the plan, figure, and in section, at fig. 4. c is the pivot-bolt, on which it vibrates to bend the rod or bar, as shown at fig. 2. E is a stud screwed firmly into the lever L, in the position shown. This stud projects up through a curved slot, d , in the frame-plate, as shown, and on it as a centre. The roller-bearing lever M vibrates to form the eye of the rod. A segmental guide-plate, G, is bolted to the under side of the frame-plate, and serves as a guide to the lever L. The roller-lever M is recessed, as shown, to receive the roller N, which works therein on a spindle, n . The lower part, g , of the lever M is hinged to the collar h , which fits on the stud E, whereby, when the lever M is actuated against the rod to be bent, the collar h turns on the stud E as a centre, and the lever M carries the roller N around and against the rod or bar, thus forming the eye, which operation will be more specially described hereafter. The roller is provided with a flange, r , to prevent the rod from being deflected upward while the eye is being formed. l is a catch pivoted to the end of the frame-plate, for the purpose of holding the lever L after the latter has put the first bend in the rod, as shown at fig. 2.

In the operation of forming the eyes, the levers L and M are placed in the positions shown at fig. 1. The rod to be bent is shown in red outline at H. It is bevelled at its end, as shown, for the purpose of forming the joint with the rod, when it is returned upon the same in the formation of the eye. This rod being heated to the proper degree, is entered between the guides C and D, and pushed forward a certain suitable distance, so that the bevelled part shall just return upon the rod when the eye is formed. The levers L and M, in practice, are proportionately longer than is now shown, and terminate in handles for operating them. The lever M is permitted by its hinge to take the position shown at fig. 1. The lever L is placed in the position shown in this figure, whereby the bar or rod H will pass between the stud E and the plate D. The lever L is then moved to the position shown at fig. 2, bending the rod H, as shown at that figure. The catch l , the end of which rested

on the lever L in its first position, now drops its catch part over the side of the lever, and holds it firmly in the second position. The lever M is then turned through the several positions M M' M'', shown at fig. 3, which operation of turning forms the eye by the action of the roller m bearing against the rod or bar in the manner indicated. The hinge serves to permit the withdrawal of the roller-flange r from contact with the stud E, so that the rod or bar can be entered between the same, or withdrawn therefrom after the eye is formed. The flange r operates in contact with the stud E, as shown, for another purpose besides the one above set forth, this latter purpose being to prevent the undue compression or drawing out of the eye while it is being formed. The plane surface of the plate B is in the same plane with the upper surface of the collar h, whereby the eye is formed straight with rod.

The peculiar advantage of my improvements consists in the fact that the eye is formed without undue compression or hammering, which latter action destroys, in a great measure, the parallel character of the fibres or grain of the metal, which parallel character is a requisite condition to the normal strength of the rod; for by hammering or other undue or unequal compression of the metal, the latter is rendered more or less defective from the crystallization of the fibres, or their induced tendency to such crystallization.

In bridges and other engineering structures, eye-rods or bars are employed to sustain a certain calculated strain, and while the strength of the rod or bar can be ascertained and relied upon, the formation of the eye, by means of hammering or equivalent compression, as heretofore done, destroys, more or less, the integrity of the metal at that point. The breaking of such eyes has been the cause of many calamitous accidents.

I am aware that a machine for bending wire has been made, which is remotely similar to the one above set forth, (see case of N. E. Perry, No. 35,255,) but this machine, aside from its bending lever, has no other point of similarity, and could not be made available for the objects above mentioned. It contemplates the bending of wire, and the nature of its construction rendering that employment possible only with it.

I claim as new, and desire to secure by Letters Patent—

1. The lever L and stud E, or their equivalents, substantially as shown and described, in combination with the plates A B C, or their equivalents, and the adjustable guide-plate D, or its equivalent, all constructed, arranged, and operating substantially as and for the purpose set forth.
2. The lever M, collar h, flanged roller N, and the stud E, or other equivalent device, substantially as shown and described, and for the purpose specified.
3. The subject-matter of the first claim, in combination with the catch l, or its equivalent, substantially as shown and described, and for the purpose set forth.
4. The improved bending apparatus herein described, operating in the manner and for the purpose substantially as set forth.

CHAS. KELLOGG.
